ICE PICK

Filed Feb. 28, 1923

UNITED STATES PATENT OFFICE.

HERBERT ELIJAH KEELER, OF CHICAGO, ILLINOIS.

ICE PICK.

Application filed February 28, 1923. Serial No. 621,877.

To all whom it may concern:

Be it known that I, HERBERT ELIJAH KEELER, a citizen of the United States, residing at Chicago, in the county of Cook and State 5 of Illinois, have invented a certain new and useful Improvement in Ice Picks, of which the following is a specification.

My invention relates to ice picks and similar devices in which it is desired to impart a blow to the acting portion of the tool for causing it to act upon the work. As the invention is particularly adapted to be applied to an ice pick, I have illustrated it and will describe it in that form. Ice picks 10 are known in which a chambered handle is slidingly mounted upon a pointed rod, for imparting a hammer blow to it when the handle descends. In such devices it is common to employ a helical compression spring 15 so that the handle may rise to initial position, when the pressure of the hand is released, without simultaneously raising the rod. Such a construction is shown in my prior Patent 1,437,425 issued December 5th, 20 25 1922. As ordinarily constructed, ice picks having helical compression springs within the handle are apt to jam, due to the buckling of the spring. According to my present invention the compression spring is dispensed with and I have employed instead a contractile or tension spring, and have thereby avoided the difficulty mentioned. 30 One of the objects of my invention, therefore, is to provide a spring of such character that buckling or jamming will be avoided. Another object of the invention is to provide means by which the handle may be rotated independently of the rod, without affecting the spring. In carrying out my 35 present invention the upper end of the spring is connected to the upper portion of the rod and the lower end of the spring is connected to the lower portion of the handle, and the connections at one end of the 40 45 50 spring are swiveled, with the result that relative rotation between the handle and the rod will neither wind nor unwind the spring, nor change its condition or characteristics. Another object of my invention 55 is to provide special details of construction which make it possible to construct the device economically and expeditiously and render the device durable and effective.

I obtain my objects by the mechanism

illustrated in the accompanying drawings 55 in which—

Figure 1 is a side view of the tool chiefly in diametral section.

Figure 2 is a top plan view.

Figure 3 is a sectional view on the line 60 3—3, Figure 1.

Figure 4 is a side view of the collar which forms one part of the swivel connection between the spring and the rod.

Figure 5 is a side view of the bushing 65 which forms a closure for the lower end of the handle in the form shown in Figure 1.

Figure 6 is an enlarged detail chiefly in diametral section showing the swivel connection between the spring and the rod. 70

Figure 7 is a side view chiefly in diametral section showing a modified construction in which the parts instead of being assembled through the lower end of the handle are assembled through the upper end thereof. 75

Figure 8 is a detail view of a simplified form of connection between the spring and the rod.

Like numerals denote like parts throughout the several views. 80

In the form selected to illustrate the invention—especially Figures 1, to 6, inclusive—the tool 1 is a pointed rod, although tools otherwise formed at the outer end may be substituted with like effect so far as the 85 principle of the invention is concerned. A chambered handle 2, having a head 3 at the top by which it may be grasped, is closed at the lower end by a bushing 4 shown separately in Figure 5. This bushing is externally threaded to screw into the lower internally threaded end of the handle and has a center bore adapted to form a guide for the rod 1. This bushing also forms an anchor 90 for the lower end of a tension spring 6. 95 While various forms of attachment of the spring to the bushing may be employed, a simple construction is shown in the drawings. According to this design the bushing has an upward facing shoulder between its upper and lower ends which forms an abutment for the spring and has an aperture 8 extending vertically through it, through which the lower end of the spring is passed. At its lower extremity the spring is peened 100 or swaged to the bushing, with the result that the spring and the bushing are firmly fastened together. 105

The upper end of the bushing forms a stop for limiting the outward movement of the collar 10 which is pinned or otherwise rigidly secured to the rod. The upper end 5 of the spring is connected in a similar manner to a sleeve 12 which is shown separately in Figure 4 and on an increased scale in Figure 6. This sleeve seats upon a collar 14 pinned or otherwise rigidly fastened to 10 the upper portion of the rod 1. Said sleeve is loosely mounted upon the rod and fits loosely within the chambered handle. Consequently the handle and the sleeve may rotate independently. A second collar 16 is 15 rigidly secured to the rod 1 above sleeve 12. While the manner of securing it may be varied, I have illustrated a form in which the upper end of the rod is screw threaded and the collar 16 constitutes a nut which 20 screws down onto it. This nut is fastened in place by a pin 18. The important characteristic is that one end of the spring has a swiveled connection with the result that the rod in the handle may be rotated with- 25 out tending to unwind or wind up the spring. In the illustrated form it is the upper end of the spring which is provided with a swiveled connection.

In operation, when the parts are assem- 30 bled as shown in Figure 1 the tension of the spring tends to eject the rod, the movement being limited by the collar 10 which engages the inner end of the bushing 4. When the operator presses down upon the handle 35 in order to impart a hammer-like blow to the upper end of the rod 1, the spring yields to permit it, and as soon as the pressure by the operator is released the parts will return to normal position, shown in Figure 1. In 40 a device of this character it might well happen that a user would rotate the rod relatively to the handle, either by intention or accident, but with my device this would have no effect upon the spring. The sleeve 12 and 45 rod 1 and handle 2 are all rotatable independently of each other, and nothing the operator can do will have any appreciable effect either to wind or unwind the spring. Thus it is impossible to damage the spring; an 50 effect which might readily occur if both ends of the spring were rigidly fastened to their associated parts 1 and 2. My device may, therefore, be regarded as fool-proof, and as 55 the spring is simply tensioned when the handle is lowered, there is no opportunity for it to buckle or become jammed. The straining of the spring instead of inducing a buckling action tends to keep it straight.

In the form shown in Figure 1 the parts 60 are assembled from the lower end of the handle. In Figure 7 I have shown a construction in which the assemblage occurs from the upper end of the handle. In this case the handle is closed at the bottom except for an aperture 20 which forms a guide

for the rod. The upper end of the handle is closed by a screw plug 22. The upper end of the spring is swiveled to the upper portion of the rod as before. At the lower end of the handle instead of the bushing 4 there is a bushing 24 which is secured to the lower portion of the handle by means of a pin 26 or other appropriate means. The lower end of the spring is anchored to this bushing 24 and the general assemblage is such that the device operates upon the same principle as before, the blow in this case being imparted by the plug 22 which engages the upper end of the rod 1.

The form of swivel connection between the spring and the member to which it is connected may be simplified as, for example, in the form shown in Figure 8. Here the spring, instead of being connected to a loose sleeve, is simply looped around the shaft 85 between the collars 14 and 16. The loop 17 loosely encircles the shaft and hence permits it to rotate independently of the spring.

It will be evident that my device is not only proof against misoperation, but is of 90 simple form and has a comparatively small number of parts. The parts are relatively simple to make and are rugged and durable, and there is little likelihood of any of them becoming out of order.

Having thus described my invention what I claim as new and desire to secure by Letters Patent is:

1. An ice pick having a pointed rod, a chambered handle slidably mounted on the rod and adapted to engage it for imparting a blow to it, a tension spring connected at one end to the upper portion of the rod and at the other end to the lower portion of the handle, and means for limiting the outward movement of the rod.

2. An ice pick having a pointed rod, a chambered handle slidably mounted on the rod and adapted to strike it, a tension spring having at one end a connection to the upper portion of the rod and at the other end a connection to the lower portion of the handle, and means for limiting the outward movement of the rod, one of said connections being a swivel connection whereby the handle may be rotated relatively to the rod without affecting the spring.

3. An ice pick having a pointed rod, a chambered handle slidably mounted on it and adapted to strike it, a tension spring connected at the lower end to the lower portion of the handle, and a swivel connection between the upper end of the spring and the upper portion of the rod.

4. An ice pick having a pointed rod, a chambered handle slidably mounted upon the rod and adapted to descend onto it for imparting to it a hammer blow, the handle and the rod being rotatable independently of each other, a helical tension spring en-

closed within the handle and encircling the rod, the lower end of the spring being anchored to the lower portion of the handle, and a sleeve swiveled to the rod at the upper portion thereof, the upper end of the spring being secured to said sleeve.

5. An ice pick having a pointed rod, a chambered handle slidably and rotatably mounted upon the rod and adapted to descend into abutting engagement with it, the lower end of the handle being apertured to form a guide for the rod, the handle being otherwise closed at the bottom, a collar fastened to the rod and adapted to engage the

lower end of the handle for limiting the 15 outward movement of the rod, and a helical tension spring located within the handle and encircling the rod and having a connection at one end to the upper portion of the rod and at the other end to the lower portion of 20 the handle, one of said connections being swiveled whereby the handle and the rod may be rotated independently of each other without producing any appreciable torsional effect upon the spring. 25

In witness whereof, I have hereunto subscribed my name.

HERBERT ELIJAH KEELER.
